UNITED STATES PATENT OFFICE.

HENRY C. MILLER, OF MILWAUKEE, WISCONSIN.

LOOSE-LEAF BINDER.

Original application filed October 30, 1922, Serial No. 597,971. Divided and this application filed September 10, 1923. Serial No. 662,022.

This invention relates to certain new and useful improvements in loose leaf binders and is a division of my application filed October 30, 1922, Serial No. 597,971.

5 This invention has for a general object to provide a loose leaf binder having scissor toggle or lazy tong means for coordinating the movements of the binder heads to clamp the leaves therebetween.

10 It is another object of this invention to provide simplified means for connecting the movable heads of a loose leaf binder and maintaining the same in parallel relation at all times.

15 A further object of this invention resides in the provision of scissor toggle or lazy tong means for connecting the binder heads of a loose leaf booklet having means for normally expanding the same and means for 20 securing the heads in any position of adjustment against the expanding means.

25 And a still further object of this invention resides in the provision of a loose leaf booklet of the character described having means capable of operation to instantly open or expand the binder heads thereof to permit free access to the leaflets secured therebetween.

With the above and other objects in view 30 which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawings, I have illustrated one complete example of the physical embodiment of my invention constructed according to the best mode I have so far devised for the practical application of the principles thereof, and in which:

45 Figure 1 is a side view of a loose leaf binder embodying my invention;

50 Figure 2 is a view looking at the end thereof with the binder heads in partly opened or expanded position, parts thereof being broken away to more clearly illustrate details of construction, and

55 Figure 3 is a view taken through Figure 1 on substantially the plane of the line 3—3 and illustrating the binder heads in full expanded or open position.

Referring now more particularly to the accompanying drawing, in which like numerals designate like parts throughout the several views, 5 and 6 designate upper and lower binder heads, respectively, between 60 which is clamped a body of leaves 7 by means of the mechanism to be hereinafter described. Pivoted to lugs 8, adjacent the ends of the heads, are upper and lower covers 9 and 10, respectively, for protecting 65 the leaves 7.

The binder heads are connected by a plurality of posts 11, preferably formed of telescoping sections in order that the heads may be readily retracted or expanded, which 70 pass through suitable openings, not shown, in the inner edges of the leaves 7, as is well known in the art. Operatively connecting the binder heads is a scissor toggle or lazy tong device, comprising two levers 75 12 and 13 which intersect and are centrally, pivotally connected by a pin 14, the ends of the levers being in turn pivotally connected with the adjacent binder heads, as hereinafter described.

The upper and lower binder heads are provided with depending flanges 15 and 16, respectively, and the upper or right end of lever 12, with reference to Figure 3, is pivotally connected with the adjacent end 80 of the flange 15 by a pivot 17 carried by said flange and passed through an arcuate slot 18 in the adjacent end of the lever and the other end thereof is pivotally secured to the adjacent end of flange 16 by a pivot 19. The upper or left end of the lever 13, with reference to Figure 3, is pivotally connected with the adjacent or left hand end of the flange 15 by a pivot 20 and the other end thereof is connected with the adjacent 85 end of the flange 16 by a pivot 21 carried by the flange and passed through an arcuate slot 22 in the lever.

With the adjacent or right hand ends of the levers 12 and 13, with reference to Figure 100 3, provided with shifting pivots, the shortening and lengthening of the distance between the pivots 17 and 19, and 20 and 21, incidental to the closing and opening of the binder heads, is readily accommodated. 105 The levers 12 and 13 are normally yieldably urged to their expanded or full open position, illustrated in Figure 3, by one or more contractile springs 23, the ends of which are connected with the levers, as at 24. 110

With this construction, the normal tendency of the binder heads 5 and 6 is to separate and they are secured in any position of adjustment, against the force of the springs 23, by a pawl 25 adapted to engage the teeth of a rack 26 carried by flange 16. Pawl 25 is carried by the short arm 27 of a bell-crank lever 28 which is pivoted at its apex to flange 15, as at 29, and has the end 30 of its long arm 31 extended to one side of the binder head to permit its ready and convenient actuation. Pawl 25 is yieldably urged to engagement with rack 26 by a spring 32, one end of which is secured to the arm 31 outwardly of pivot 29, as at 33, and the other end of which is secured to an ear or lug 34 carried by the flange 15, as at 35.

The scissor toggle or lazy tong means are entirely concealed from view by overlapping end members 36 and 37, carried by the flanges 15 and 16 of the binder heads 5 and 6, respectively; and by end members 38 carried by one of the binding heads, as illustrated in the drawing. The extensions 36 and 37 pass one behind the other when the binder heads are closed or retracted as illustrated in Figures 1 and 2.

When it is desired to either add new sheets or remove any of the sheets, the end 30 of the lever 28 is moved against the action of spring 32 and the pawl 25 disengaged from the teeth of the ratchet member 26; as a result of which the energy of springs 23 is

released and the toggle or lazy tong device opened or expanded. The binder heads may be either fully expanded, as illustrated in Figure 3, or else partially expanded by permitting the engagement of the ratchet 25 with the desired teeth of the ratchet 26.

When it is desired to close the binder heads, they are moved together against the action of the springs 23, the pawl 25 slipping over the ratchet 26 by reason of the shape of its outer end and engaging behind the ratchet teeth as will be readily obvious.

What I claim as my invention is:

A loose leaf binder, comprising a pair of binder heads, means connecting the binder heads, means tending to normally urge the binder heads apart, a rack member carried by one binder head, teeth on said rack member, a bell-crank lever, means pivotally connecting the bell-crank lever at its apex to said other binder head, said bell-crank lever having a long arm with its outer end adjacent one side of the binder and its other end positioned adjacent said rack, and a pawl formed on said other end of said bell-crank lever and adapted to selectively engage the teeth of the rack to secure the binder head in any position of adjustment against said urging means.

In testimony whereof I affix my signature.

HENRY C. MILLER.
